V. NIVOIS.
CIGARETTE CASE.
APPLICATION FILED FEB. 27, 1917.

1,232,073.

Patented July 3, 1917

Inventor.

Victor Nivore.

By his Attorney,

UNITED STATES PATENT OFFICE

VICTOR NIVOIS, OF BROOKLYN, NEW YORK.

CIGARETTE-CASE

1,232,073.

Specification of Letters Patent.

Patented July 3, 1917.

Original application filed September 25, 1914, Serial No. 863,487. Divided and this application filed February 27, 1917. Serial No. 151,250.

To all whom it may concern:

Be it known that I, VICTOR NIVOIS, a citizen of France, residing at Brooklyn, in the county of Kings and State of New York, have invented certain new and useful Improvements in Cigarette-Cases, of which the following is a specification.

This invention relates to cases for holding cigarettes, cigars and other articles and has particular application to a case of the type having a pair of hingedly connected dished cover or case sections and an article holder or carrier located therebetween and adapted to be concealed by such sections when the case is closed and to be exposed to view when the case is opened, this application being a division of my co-pending application for cigarette case filed September 25, 1914, Serial No. 863,487. In prior cases of this type with which I am acquainted, where the holder is adapted to assume an upstanding position between the case sections when the latter are moved to open position, the holder has been positively or immovably held in such upstanding position so that any pressure against the holder toward one or the other of the case sections would result in bending, distorting or breaking the positive holding means employed. Such objection I entirely overcome in my case by providing means that will permit of the holder being readily moved bodily toward and into nested relation with either of the case sections without in any manner bending, straining, distorting, or breaking any of the connections.

It is also my purpose to provide a case of this character having a holder or carrier which embodies a pair of spaced plates or walls normally arranged in substantial parallelism, each plate or wall having a series of vertically arranged substantially parallel grooves or corrugations formed therein with the grooves of one wall arranged opposite to the grooves of the other wall so that individual cigarette pockets are provided for retaining the cigarettes without pinching or compressing the latter.

Furthermore, the holder or carrier of the case may have its corrugated plates or walls movable and separable relative to each other so that each plate is adapted to be nested in its associated or adjacent case section, or the two plates or walls may be permanently connected at their connecting side edges so

that the walls are at all times preserved in their substantially parallel relation. But whether the plates be separable relative to each other or permanently connected, as just mentioned, the holder as an entirety will be so supported when in upright position, that it may easily be shifted bodily from such position toward and into nested relation with either of the case sections without the liability of breaking or bending strains being imparted to the sections or to the connecting parts. Another object of the invention is the provision of a cigarette case of this type wherein the filling or loading of the carrier or holder with the cigarettes may be accomplished quickly, conveniently and with facility.

With the above recited objects and others of a similar nature in view my invention consists in the construction, combination and arrangement of parts set forth in and falling within the scope of the appended claims.

In the accompanying drawings:

Figure 1 is a perspective view of a case embodying my invention and showing the cover or case sections in open position with the holder composed of two separable walls or plates held upright therebetween.

Fig. 2 is a fragmentary vertical section upon an enlarged scale taken at the point of connection between the sections of the case and particularly illustrating the means for attaching the holder in position and for maintaining it in its position between the two sections.

Fig. 3 is a fragmentary vertical sectional view upon an enlarged scale showing the case sections in their opened or horizontal position and also showing the two holder plates partially separated.

Fig. 4 is a top plan view of the open case shown in Fig. 1, parts of the case or cover sections being broken away.

Fig. 5 is a perspective view of a shoe which is preferably embodied in the device.

Fig. 6 is a longitudinal section through the shoe shown in Fig. 5 and also illustrating the parts associated with the shoe.

Fig. 7 is a view similar to Fig. 2 but illustrating the manner in which the holder may fold against either cover or case section of the case.

Fig. 8 is a fragmentary vertical sectional view showing the case in open position with

one of the holder plates nested within its associated or adjacent case or cover section, the other plate section of the holder being shown as separated from the first mentioned plate section, the parts being in such position as to facilitate the loading or filling of the case with cigarettes.

Fig. 9 is a modified form of the invention showing the two walls or plates of the holder permanently connected at their side edges.

Referring now to the drawings in detail, and particularly to Figs. 1 to 8 inclusive, the two cover or case sections are shown at 11 and 12 and are hingedly connected as at 13. These sections 11 and 12 are preferably formed of thin metal sheets pressed into dish-like shape so that when brought together they inclose a space for the cigarettes or other articles. The hinge connection 13 is preferably produced by forming sleeves 15 integrally on the case sections 11 and 12 and connecting these sleeves by means of a central hinge bar or pintle 16, said pintle preferably having extensions 17 adjacent the ends thereof and these extensions may be formed integral with the pintle by bending up the ends of the latter as shown in Fig. 1. The cigarettes are intended to be supported or carried in a holder 18 which is adapted to be supported in upright position, by means of a shoe 19 mounted on the pintle, when the case is opened as shown in Fig. 1. The preferred form of the shoe is shown in Fig. 5, and preferably comprises a small roll of metal having a longitudinal bore 20 to loosely receive the pintle. In order to yieldingly maintain this shoe in position so that when the case sections 11 and 12 are opened the shoe will be held in mid-position to support the holder 18 upright, I provide a pair of springs 21 which are of helical form and disposed around the pintle adjacent each end of the shoe. These coils or springs 21 may be made of a single wire connected by an integral bar 22 extending through a small bore 23 in the shoe, the outer ends of the springs 21 having lateral extensions 24 which preferably engage respectively with the hinged edge of each case or cover section so that the springs tend to swing the two sections apart, or into open position. The holder proper is intended to be held in yielding engagement with the shoe, and for this purpose I provide a recess or groove 25 on the top surface of the shoe 19, which groove is intended to accommodate the lower edge portion of the container, as shown at 26 in Fig. 1. The carrier 18 which is intended to hold the cigarettes is formed of two oppositely disposed corrugated plates or walls 27 and 28, the plates or walls of the carrier being movable with respect to each other so they can be separated if desired. As will be seen by reference to Fig. 1 the corrugations or grooves

of the plates or walls are run vertically when the holder is in its upstanding position, and the corrugations or grooves of one of the walls are arranged opposite to the corrugations or grooves of the other wall whereby individual cigarette pockets are provided which will retain the cigarettes without pinching or compressing the latter, said pockets being normally open at one end, and as will be seen by reference to Fig. 1, one of the walls is preferably made higher than the other wall to provide a free marginal edge portion which will assist in guiding the cigarettes into the pockets of the holder. One of these plates, for instance, the plate 27 is attached rigidly near its ends to the extensions 17 of the pintle 16 which connects the case or cover sections 11 and 12, as aforesaid. The other plate 28 in turn may be attached to the lower edge of the plate 27 by any suitable spring hinge 29. The walls or plates 27 and 28 constituting the holder or carrier are not only movable with respect to each other so they can be separated, if desired, and each swung to a nested position within its associated or adjacent case section, but the holder, when occupying its normal cigarette holding position, as when the two plates 27 and 28 extend in parallelism as shown in Fig. 2, may be swung bodily against or into nested position relative to one or the other of the cover or case sections 11 and 12, as shown in Fig. 7. With the case embodied in this invention, it is evident that when the case is opened, the sections 11 and 12, will be swung apart and the shoe 19 in the operation of its recess 25 will yieldingly maintain the cigarette holder 18 in an intermediate position between these case sections; or in other words, it will maintain the holder in mid-position in the angle formed between the two sections 11 and 12, as they open. If the cigarette case is lying open in the position illustrated in Fig. 1, the container may be swung over toward either of the sections 11 or 12, by using sufficient force to disengage the lower edge of the holder from the recess 25, as shown in Fig. 7. Then if desired, one of the plates of the holder may be separated or drawn away from the other or companion plate shown in Fig. 8, and the cigarettes may be rapidly placed in position, in bulk, by simply depositing the desired number in the corrugations of that plate of the holder which is lying over against its associated cover section. Inasmuch as the shoe 19 is not attached directly to the pintle, but may be said to have a floating attachment to the latter, it is necessary to prevent the shoe from being rotated with the carrier when moved down as above mentioned. To do this I prefer to provide means on the shoe for engaging the sections of the case to prevent

vent such rotation if the case is lying open. For this purpose I prefer to provide the inner or lower side of the shoe with a projection 29' which may be in the form of a longitudinal rib. When the case is lying open, this rib or projection lies between the adjacent edges of the sections 11 and 12, as shown more clearly in Fig. 2. Obviously this projection 29' will prevent the 10 rotation of the shoe and permit the holder to be swung or moved independently of such shoe. On each side of the recess 25 the shoe is provided with a longitudinal shoulder 30 and these shoulders insure that if the case is closed, after swinging over the 15 holder as suggested, the shoe will come into a mid position, such as will bring the edge of the holder into the recess 25. Hence, when the case is re-opened, the shoe will 20 assume and maintain a neutral or mid position between the sections of the case and will maintain the cigarette holder projecting into the angle therebetween, as set forth above.

25 From the above description taken in connection with the accompanying drawings, it will be obvious that the convenient manipulation of the case, say in opening and closing the same, and in filling and removing 30 the cigarettes therefrom, is greatly facilitated by the structural features thereof, for not only will the holder be maintained in upright position when the case is opened out flat, as shown in Fig. 1, but the two 35 plates or walls of the holder may, as will be apparent, be separated or moved in opposite directions away from each other as shown in Fig. 3, and each of such plates nested in its adjacent cover or case section, as will be 40 understood by reference to Fig. 8 so that the loading or filling of the case with the cigarettes may be readily accomplished, and furthermore, if desired, the complete holder formed when its plates or walls are in par- 45 allelism, may be bodily swung into either of the case or cover sections.

50 In Fig. 9 I have shown a slightly modified form of the invention wherein the plates or walls of the holder are made rigid with each other, and in this instance the cigarette holder is made of a single plate bent or doubled as at 31 and at the end of this double corrugated plate the extensions 55 32 of the pintle 33 are attached rigidly. The lower edges of the carrier of this form may be provided with downwardly offset 60 ribs or projections 34 which may engage the recess in the shoe of the case as heretofore described for the construction shown in Figs. 1 to 8.

65 What I claim is:

1. A pocket cigarette case comprising a pair of dished case sections having a hinged connection therebetween so as to permit said sections to be brought together in closed po-

sition and opened out in substantial alinement one with the other, an article holder supported to be incased between the case sections when the latter are in closed position and to be yieldably held in an upright position when the case sections are opened out, said article holder comprising a pair of similar oppositely disposed wall members pivoted for independent movement toward and from each other and either being adapted to be nested within its associated case section when the two case sections are opened out in substantial alinement with each other, and means for holding the said walls of the article holder with their side edges in co-operative abutting relation to provide an upstanding article receiving compartment when the case sections are opened out in substantial alinement with one another.

2. A pocket cigarette case comprising a pair of dished case sections having a hinge pintle connection therebetween permitting said sections to be closed together and opened out in substantial alinement with one another, an article holder supported from said pintle and adapted to be incased between the case sections when the latter are closed together and to be movably supported in an upright position when the case sections are opened out, said article holder comprising similar oppositely disposed wall members pivoted for relative movement toward and from each other and either member capable of being nested within its associated case section when the two sections are opened out in substantial alinement, and means for holding the side edges of said walls of the article holder in abutting relation to provide an upstanding article receiving compartment when the case sections are opened out in substantial alinement.

3. A pocket cigarette case comprising a pair of dished case sections having a hinged connection therebetween so as to permit said sections to be brought together in closed position and opened out in substantial alinement one with the other, an article holder supported to be incased between the case sections when the latter are in closed position, and to be movably held in an upright position when the case sections are opened out, said article holder comprising a pair of oppositely disposed wall members, each of said wall members having a series of substantially parallel grooves or corrugations formed therein, the grooves of one of said wall members being arranged opposite to the grooves of the other of said wall members whereby individual cigarette pockets are provided for retaining the cigarettes, said pockets being normally open at one end, said wall members being pivoted for independent movement toward and from each other and either being adapted to be

nested within its associated case section when the two case sections are opened out in substantial alinement with each other, and means for holding the side edges of 5 said walls of the article holder in cooperative abutting relation to provide an upstanding article receiving compartment when the case sections are opened out in substantial alinement with one another.

- 10 4. A pocket cigarette case comprising a pair of dished case-sections having a hinge pintle connection therebetween permitting said sections to be closed together and opened out in substantial alinement with one 15 another, an article-holder supported from said pintle and adapted to be incased between the case-sections when the latter are closed together, and to be yieldably supported in an upright position when the case 20 sections are opened out, said article holder comprising oppositely disposed wall members pivoted for relative movement toward and from each other and either member capable of being nested within its associated 25 case section when the two sections are opened out in substantial alinement, each of said wall members having a series of vertically arranged substantially parallel grooves or corrugations formed therein, the grooves 30 of one of said walls being arranged opposite to the grooves of the other wall, whereby individual cigarette pockets are provided

for retaining the cigarettes without compressing the latter, said pockets being normally open at one end, and means for holding the said walls of the article holder in closed relation to provide an upstanding article receiving compartment when the case sections are opened out in substantial alinement.

35

5. In a cigarette case, a carrier including two spaced walls normally arranged in substantial parallelism, each of said walls having a series of vertically arranged substantially parallel grooves or corrugations 40 formed therein, the grooves of one of said walls being arranged opposite to the grooves of the other wall, whereby individual cigarette pockets are provided for retaining the cigarettes without compressing the latter, 45 said pockets being normally open at one end, one of said walls being higher than the other wall to provide a free marginal edge portion for guiding the cigarettes into the pockets of the carrier, hinged case sections 50 for overlying the walls of the carrier to inclose the latter when the case sections are brought together, and means for causing said carrier to maintain a position at an angle to the case sections when the latter are 55 in an open position.

55

In testimony whereof I affix my signature.

VICTOR NIVOIS.
